UNITED STATES PATENT OFFICE.

WILLIAM VAN DEN HEUVEL, OF LOS ANGELES, CALIFORNIA.

COMBINATION TRAVELING-CRANE CABLEWAY.

1,325,818.

Specification of Letters Patent. Patented Dec. 23, 1919.

Application filed April 1, 1918. Serial No. 226,093.

To all whom it may concern:

Be it known that I, WILLIAM VAN DEN HEUVEL, a subject of The Netherlands, residing at Los Angeles, in the county of Los Angeles, State of California, have invented new and useful Improvements in Combination Traveling-Crane Cableways, of which the following is a specification.

This invention relates to devices used for transporting and handling materials; and relates more particularly to a traveling crane cableway system adapted for use in shipyards and the like, or wherever and in whatever situations it is desired to handle heavy materials over a large ground area. The difficulties which my system is particularly designed to overcome are peculiarly found in shipyards; and accordingly I illustrate and describe my system as applied to shipyards. From the specific description thus given, it will be readily understood how my system may be applied to other classes of transportation or handling of materials.

Particularly as applied to shipbuilding, there have been great difficulties encountered in the economical and efficient handling of the heavy materials and parts, and in the provision of efficient and economical appliances, devices and apparatus for doing the required work. It is of course theoretically possible to build structural traveling cranes of the kind used for shop transportation, and of a size large enough to carry material over a single ship; but such structures are extremely expensive and have their limitations. Although there may be no limitation upon the length of travel of an ordinary beam crane, there is a practical limitation upon its span; and so it has proven practically impossible to handle heavy materials over a whole yard, or over a number of slips, with a single mechanism. A single mechanism or system, besides having the advantage of relative inexpensiveness for original construction and installation, has the exceedingly great advantage of being able to handle a load from any point to any other point in a whole yard or over a number of slips without having to drop the load and pick it up again; and has the advantage of being able to move

from slip to slip, instead of being confined to a single slip, as heretofore.

Although attempts have been made in the direction of using traveling crane cableways and the like, no success has been attendant largely on account of the nonpositiveness of operation of such system.

It is an object of this invention to overcome the difficulties herein spoken of; to provide a traveling crane cableway system which may be extended to cover a large yard or a number of slips, large enough to handle material over the length of the largest ship, and capable of extension to cover any number of slips which lie side by side (capable in fact, of indefinite extension in this direction); and to provide a system which is relatively inexpensive of construction, installation, and operation. In fact, it is an object of this invention to provide a system which has the advantages of the rigid structural traveling crane system, together with the advantages of a cableway system, which allow it to cover a large area. And it is an object of this invention to specifically provide a form of system which will enable shipbuilders to economically and efficiently transport and handle materials, plates, parts, etc., with the highest speed, accuracy and economy.

Underlying my system is the principle of positiveness of operation, control and placement of loads. To gain this positiveness I employ a rigidity of the fundamental structure which, so far as I am aware, has hitherto been unknown in any traveling cableway system. In laying out my system for use in shipyards, I lay along the upper and lower limits of a slip or slips an elevated track-way supported upon towers and of such construction as to be rigid under all the strains which it is designed to carry. This elevated track-way is high enough to handle materials high as desired—over the highest work carried on in the slip—and is high enough to allow the ship to pass under when launched. The elevated trackways are supported upon towers sufficiently widely spaced at the lower end to allow passage of a hull between them and at the upper end to allow free transportation and movement of materials, parts, etc., under

the upper trackway. The cableway is suspended between traveling bogies—travelers—upon the opposite elevated trackways; and the primary strain to which the elevated trackways are subjected are those transmitted to it through the suspension cable or cables. These strains, necessarily large, necessitate special design and construction of the trackways and the supporting structure and towers.

Besides these general features of my system there are certain other detailed features embodied in the general application of my system, and certain detailed and specific features embodied in a specific application of my system to a particular service. All of such features, and the general objects and accomplishments of my invention and system, will be best understood from the following detailed description of a specific form of system embodying the invention and adapted and designed particularly for shipbuilding service. For the purpose of this description I refer to the accompanying drawings in which—

Figure 1 is a side elevation showing the application of my system to ship building service; Fig. 2 is a plan showing the same; Fig. 3 is an enlarged transverse section showing a section of the upper or shop-end track and showing a bogie thereon, in section; Fig. 4 is an enlarged vertical section of parts shown in Fig. 3; Fig. 5 is a detail section taken on line 5 of Fig. 3; Fig. 6 is a sectional plan of a bogie; Fig. 7 is a horizontal detail section on line 7 of Fig. 4; Fig. 8 is a rear side elevation, and parts being in section, of a pair of bogies; Fig. 9 is a diagram showing the electrical connections to and between the bogies of each pair; Fig. 10 is a detail showing an interconnection between controllers for the bogies; Fig. 11 is a view similar to Fig. 3 of a bogie at the water end of the system; Fig. 12 is a plan of the same.

I shall first explain the general structural and mechanical and operative features of the system and then describe the details of the different parts. The elevated trackway 20 is placed across the upper or land end of a slip or slips. These elevated trackway structures may extend as far as desired or necessary to accommodate any number of slips. They are supported upon suitable thrust towers 22 and 23 set upon heavy foundations 24 of concrete or any other suitable material. Towers 23 at the lower end of the slips may be made narrower than those at the upper end so as to increase as much as possible the effective clear width between adjacent towers—so as to give as much clear beam room for a hull to pass through as possible without unduly lengthening the span of the track structure 21 between the towers. The towers at the upper or land

end of the slips may be somewhat wider in construction; but it is a feature of the construction in general that ample room is left between towers to allow free transportation and movement of materials and parts without obstruction. At the upper or land end of the system, the shop structures may be incorporated with or built adjacent to the tower structures, as is indicated at 25. The arrangement is such that materials and parts may be moved out of the shops into the spaces between the towers 22 and directly under the carriers, where they may be immediately picked up and transported to any part of the yard. That is, referring to the drawings, material delivered at the point designated generally by the letter D (just outside the shop structures) may be picked up without any further handling or transportation and handled thenceforth by the carriers on the cableway system.

Upon the upper elevated trackways 20 I mount any desired number of traveling bogies B; and upon the lower trackways 21 I mount a corresponding number of bogies B'. Between each of the two bogies which constitute a pair I suspend a suspension or track cable S. Upon each track cable S I operate a carrier on trolley C. These trolleys C form points of suspension for lifting and carrying tackle L; and means are provided, through the medium of trolleying cables T for trolleying the trolleys back and forth along the suspension cables S. And the hoist cables H provide means for controlling and operating the hoisting and lowering of the lifting tackle L wherever the trolley C may be upon cable S.

All of the operations, including the movement of the bogies in pairs along their tracks, the trolleying of the trolleys along the track cables and the operation of the lifting tackle, are controlled from the upper bogie B of each pair. There may be, as I have said before, as many pairs of bogies as desired in a single system; and it will be obvious that any number of these bogies may be concentrated in any given portion of the tracks, so as to concentrate their services upon any given portion of the yard. The operator for each pair of bogies is situated in bogie B, above the slips where he commands a view of all points. This concentration of the bogies and of the cableway is limited only by the necessary size of the bogies themselves.

From what has been said so far, it will be seen that the principal strains upon the elevated trackways are primarily horizontal and toward each other. The towers of course 125 must carry these strains; and they are accordingly designed substantially in the manner shown in the drawings in such a manner as to transmit a great deal of the strain directly through their forward compression 130

members or columns 22^a and 23^a to the forward foundations. Under these circumstances the rear column members 22^b and 23^b become strained in tension; and the rear foundations are constructed as anchors. 5

Besides these horizontal stresses (or diagonal stresses in which the horizontal component is comparatively large) the towers are of course subjected to vertical downward 10 stresses due to the weight of the structure itself and due to the weight of the bogies and due also to the horizontal component of the stresses transmitted to the bogies, and thus to the structures, through the cables.

15 The track structures 20 and 21 are subjected to similar strains, both vertical and horizontal. The track structures are consequently designed substantially in box girder form with their principal strength as beams 20 in a horizontal direction. The upper longitudinal members 30 and 31 of the track structures form the stringers upon which rails 32 are laid. The bogies are provided with supporting wheels 33 running on rails 25 32. The rear longitudinal members 31 carry heavy rails 34 standing out in a horizontal plane behind the members 31; and the bogies are provided with a suitable number of flanged wheels 35 running upon these rails. 30

It is through these flanged wheels 35 that the horizontal strains are transmitted from the bogie to the track structure; and I consequently make special provision for efficient transmission of these strains through the 35 bogie structure to the wheels 35; and also make special provision for strengthening and reinforcing the member 31. This I do by placing another longitudinal member 31^a near the longitudinal member 30 of the 40 track structure and by then inter-bracing the members 31 and 31^a with the struts and braces 31^b; so that in effect the member 31 becomes the upper chord and the member 31^a becomes the lower chord of a structural arrangement 45 adapted to efficiently carry the horizontal loads imposed upon the track rail. Both these members 31 and 31^a may be constructed of composite wood and steel as indicated at 31^c and 31^d. From the rear chord 31 the 50 horizontal strains are transmitted through structural members indicated at 31^e to the lower longitudinal members 31^f of the track structure, whence they are transmitted to the towers and thence to the foundations. 55

The bogie frame work is made up principally of transverse beams 36 and longitudinal beams or connections 37. A suitable flooring may be put over the frame work as indicated at 38 and the various machinery 60 of the bogie mounted upon the flooring and connected with the frame work. The track cable C is in each case connected to a bracket 60 on the bogie which bracket is mounted between the two central channel beams 36^a, 65 of the bogie. A clevis for the cable is con-

nected to the bracket at the point 61 and this point 61 is close to and directly on a horizontal line with the tread of forward rail 32 and also on a horizontal line with the tread of wheels 35 on rail 34. In order to 70 accomplish this arrangement and construction the forward rail 32 is below the rear rail 32, the forward longitudinal member 30 of the track structure being below the rear longitudinal member 31. The result of this 75 arrangement is that the horizontal component of the strain transmitted by cable S to the bogie is transmitted directly in a horizontal plane from the point 61 to the rail 34. This results in the fact that rail 34 carries 80 all of the horizontal stress and none of the horizontal stress is put upon the other two rails. Furthermore the fact that this horizontal stress is transmitted in the horizontal plane of the tread of forward rail 22 and is 85 transmitted entirely to thrust rail 34, precludes this horizontal stress from forming a turning moment which would tend to tip the bogie on its track. In other words, by the arrangement here described, I have 90 placed all of the horizontal stress component on the rail 34 and thus upon the structure 31, 31^a, 31^b; and I have placed all of the vertical stress component upon the rails 32. The two stress components being thus 95 segregated, the corresponding stresses are transmitted to the track structure and to the towers through their structural members.

Wheels 35, which bear on rail 34, are carried 100 on axles 63 mounted in bearings 64, which slide in guide blocks 65 and are pressed by heavy compensation springs 66 toward the rail 34. These compensation springs serve the purpose of keeping the 105 load equally distributed on the four wheels 35. Guide block 65 are mounted upon horizontal plates 67 and 68 which plates are secured to the back plate 69 and are braced and stiffened by angles or other members as 110 shown at 70. The black plate 69 and the horizontal plates 67 and 68 are connected to the beams 36 by vertical plates 71. The whole structure is such as to efficiently transmit the horizontal strain from the beams 36 115 to the wheels 35 and distribute that strain through the wheels onto the rail 34.

The bogies B and B' are traversed along their respective tracks through the medium of a single traversing cable on each track. 120 The traversing cable T' is anchored at each end as indicated at 40; and the anchorage means shown at 40^a may also be a bumper or buffer means to limit the movement of the bogies. In each bogie there is a traversing 125 mechanism consisting of a drum or drums 41 and 42 around which the cable T' passes. The traversing drum 41 is operated from a motor M through the connecting medium of gearing 42, shaft 43 and connection mecha-

180

nism (a clutch mechanism) 45 connecting with shaft 44 of drum 41. This same motor M performs also the office of trolleying the trolley C along the cable S. The trolleying cable T winds over the drum 48 which is driven from shaft 43 through the medium of gearing 46 connecting to shaft 47 of the trolleying drum. The mechanism at 45 may be a clutch mechanism whose function is to connect the shaft 43 with either the shaft 44 or the shaft 43^a. These connections may be controlled by levers 52 and 53. The function of drum 48 is merely to wind the trolleying cable T back and forth, this cable being endless and passing over a pulley or sheave 54 in the water-end bogie B'. The water-end bogie is, in its general structure, the same as the shop-end bogie B; but it is only equipped with a single motor M'' of suitable size for operating the traversing drum 41 carrying the traversing cable T. The motor M'' of this bogie B' is controlled from the bogie B in the manner hereinafter described. The hoisting cable H is merely anchored to the bogie B'. In the bogie B the hoisting cable H passes in over a sheave 49 onto hoisting drum 50 which is operated through the medium of gearing 51 directly from the hoist motor M'. This hoisting cable H passes over sheaves 59 in the trolley C and passes down in a loop around the sheave 59 in the lifting tackle L. It will be seen that the operation of drum 50 will be to raise and lower the lifting tackle, which may be done under perfect control at all times.

The electrical connections are indicated in Fig. 11. Current is fed to the bogies B through the medium of wires W mounted on the track structure and through the medium of any suitable contact mechanism mounted on the bogie. The bogie B is provided with a series of controllers R¹, R², R³, etc., connected by wires 76 to feed wires W. Controller R¹ may be connected by wires 77 to motor M of controller B, and controller R² may be connected by bars 78 to motor M'' of bogie B' (the wires 78 being supported between the two bogies on a messenger wire indicated at M). By properly actuating these two controllers R¹ and R², the two bogies of each pair may be moved back and forth on their respective ways opposite to each other; or each bogie may be, to a certain extent, traversed independently of the other. I may, if I so wish, put a mechanical connecting bar or the like, as shown at 80, between the controller handles of controllers R¹ and R² so as to cause these two controllers to work together and cause the two bogies B and B' to be traversed in coöperation with each other. The controller R³ may be connected by wires 81 to hoist motor M' for causing proper operation of that motor. The mechanical con-

nection at 80 may be of such a nature as to be easily applied and removed (may be a removable connecting bar with eyes 80^a at each end adapted to be slipped over the handles 80^b of the controllers) so that means is thereby provided for operating the bogies either co-operatively or independently. By independent operation, and by placing the bogies and cable S in somewhat diagonal relation, the cable may be tightened. Furthermore, a load may be moved laterally across a slip (especially near either end) by the movement of one bogie.

The operation of my system will now be readily understood. The operator who controls a pair of bogies is situated in the bogie B well above the scene of operations. By proper manipulation of the controllers he can traverse the pair of bogies to any desired position on the track ways. He may then move the trolley C to any desired position on cable S to pick up a load on the lifting tackle L. Having done this, he may then hoist the load to any desired height, and then, by trolleying and traversing action, he may move the load directly to any point within the limits covered by the system. Having reached the desired point, the load may be lowered and released. No transference of load is necessary in moving from any one point to any other point in the whole system. Each pair of bogies (each cable-way) may be moved from slip to slip, past the supporting towers; and any number may be concentrated in any one slip for concentrated, simultaneous or combined use. This is a feature of very great utility.

Great accuracy and despatch of operation and of placement of load is possible. The suspension or track cables are rigidly supported at their ends; and the supporting structures and the track cable itself are preferably sufficiently rigid so as to not have any objectionable amount of resiliency under the heaviest loads carried. Consequently, it is possible and practicable to put the trolley C definitely in any position desired. It is this definiteness of operation, and flexibility of application over a wide area, which is a substantial feature of my invention and to which the following claims are in part directed. These claims are intended to cover broadly the scope of this invention without being limited to the various details herein set forth. I have described these details for the purpose of making my invention readily intelligible rather than for the purpose of specifying limitations to the invention; and I accordingly do not wish my invention to be understood as limited by this detailed description.

Having described a preferred form of my invention, I claim:

1. A traveling cableway system, embodying in combination a pair of rigid elevated

track structures, a traveling bogie on each structure, a track cable suspended between the bogies, and means to either coöperatively or independently control and cause movement of the two bogies.

2. A traveling cableway system, embodying in combination a pair of rigid elevated track structures, a traveling bogie on each structure, a track cable suspended between the bogies, a trolley on the track cable, means in one bogie for moving the trolley back and forth along the track cable, a lifting tackle on the trolley, means in the same bogie for operating said lifting tackle, and means in the same bogie to control and cause traversing movement of the two bogies along their track structures.

3. A traveling cableway system, embodying in combination a pair of rigid elevated track structures, a traveling bogie on each structure, and a track cable suspended between the bogies, motor operated mechanism in each bogie for traversing it along its track structure, a trolley on the track structure, a trolley on the track cable, motor operated mechanism in one bogie and a trolleying cable operated thereby extending between the two bogies and connected to the trolley for moving the trolley back and forth along the track cable, a lifting tackle on the trolley, a hoist cable to operate the lifting tackle, a motor operated mechanism in said bogie for operating the hoist cable, and controlling means in said bogie for controlling all the motor operated mechanisms.

4. A traveling cableway system, embodying in combination a pair of rigid elevated track structures, a traveling bogie on each structure, and a track cable suspended between the bogies, motor operated mechanism in each bogie for traversing it along its track structure, a trolley on the track cable, motor operated mechanism in one bogie and a trolleying cable operated thereby extending between the two bogies and connected to the trolley for moving the trolley back and forth along the track cable, a lifting tackle on the trolley, a hoist cable to operate the lifting tackle, a motor operated mechanism in said bogie for operating the hoist cable, and controlling means in said bogie for controlling all the motor operated mechanisms and for controlling in unison the two traversing mechanisms of the two bogies.

5. In a system of the character described, a trackway embodying two longitudinal rail carrying members spaced horizontally and one lower than the other, supporting rails upon said members and a horizontal thrust rail on the back side of the higher member, a bogie frame having wheels resting on the supporting rails and wheels bearing against the thrust rail, and a suspension cable attached to the bogie frame at a point near the lower forward rail.

6. In a system of the character described, a trackway embodying two longitudinal rail carrying members spaced horizontally and one lower than the other, supporting rails upon said members and a horizontal thrust rail on the back side of the higher member, a bogie frame having wheels resting on the supporting rails and wheels bearing against the thrust rail, and a suspension cable attached to the bogie frame at a point near the lower forward rail; the point of cable attachment, the tread of the lower forward rail and the tread of the rear thrust rail being substantially in a horizontal plane.

7. In a system of the character described, a trackway embodying two longitudinal rail carrying members spaced horizontally and one lower than the other, supporting rails upon said members and a horizontal thrust rail on the back side of the higher member, a bogie frame having wheels resting on the supporting rails and wheels bearing against the thrust rail, and a suspension cable attached to the bogie frame at a point near the lower forward rail, and a horizontal stress receiving and transmitting structure of which said upper rail carrying member forms a chord.

8. In a system of the character described, a trackway, a bogie adapted to travel on the trackway, a suspension cable attached to the bogie at a point substantially in the horizontal plane of a tread of the bogie on the trackway, and a horizontal-thrust means for the bogie situated substantially in said horizontal plane.

9. In a system of the character described, a trackway having a rail adapted to receive vertical thrust, a rail adapted to receive horizontal thrust, a bogie on the trackway supported by the vertical thrust rail and bearing against the horizontal thrust rail, the treads of the two rails being substantially in a horizontal plane, and a suspension cable attached to the bogie at a point substantially in the said horizontal plane.

10. In a system of the character described, a trackway having a rail adapted to receive vertical thrust, a rail adapted to receive horizontal thrust, a bogie in the trackway supported by the vertical thrust rail and bearing against the horizontal thrust rail, the treads of the two rails being substantially in a horizontal plane, and a suspension cable attached to the bogie at a point substantially in the said horizontal plane, and close to the vertical thrust rail.

11. A traveling cableway system, embodying in combination a pair of rigid elevated track structures, a traveling bogie on each structure, a track cable suspended between the bogies, a trolley on the track cable, and means located in one of said bogies for controlling the trolley and controlling the two bogies.

12. In a system of the character described, a trackway, a bogie adapted to travel on the trackway, a suspension cable attached to the bogie and exerting a substantially horizontal pull thereon, and a horizontal-thrust means for the bogie situated substantially in the plane of the cable pull thereon.

In witness that I claim the foregoing, I have hereunto subscribed my name this 1st day of March, 1918.

WILLIAM VAN DEN HEUVEL
Witness:
VIRGINIA I. BERNINGER.
